United States Patent Office

Des. 173,595
Patented Nov. 30, 1954

173,595

ASH TRAY OR SIMILAR ARTICLE

Anton F. Sulak, Seattle, Wash.

Application March 22, 1954, Serial No. 29,648

Term of patent 3½ years

(Cl. D85—2)

Fig. 1

To all whom it may concern:

Be it known that I, Anton F. Sulak, a citizen of the United States, residing at Seattle, in the county of King, State of Washington, have invented a new, original, and ornamental Design for an Ash Tray or Similar Article, of which the following is a specification, reference being had to the accompanying drawing, forming a part thereof.

Fig. 1 is a perspective view of an ash tray or similar article, showing my new design;

Fig. 2 is a side elevational view thereof; and

Fig. 3 is a top plan view thereof.

I claim:
The ornamental design for an ash tray or similar article, as shown.
